UNITED STATES PATENT OFFICE.

LUCIE HARDMON COALE, OF WARREN, OHIO.

DESIGN FOR AN EARPIECE FOR TELEPHONE-RECEIVERS.

SPECIFICATION forming part of Design No. 32,779, dated June 5, 1900.

Application filed April 23, 1900. Serial No. 14,051. Term of patent 14 years.

To all whom it may concern:

Be it known that I, LUCIE HARDMON COALE, a citizen of the United States, residing at Warren, in the county of Trumbull and State of Ohio, have invented a new and original Design for an Earpiece for a Telephone-Receiver, of which the following is a specification.

This invention relates to a new and original design for an earpiece for a telephone-receiver, and the essential feature resides in the circular body having a concentric offset of circular form from which a tubular conical projection extends.

In the drawings, Figure 1 is a transverse vertical section of an earpiece for a telephone-receiver embodying the features of the design. Fig. 2 is a top plan view of the same.

Similar numerals of reference are employed to indicate corresponding parts in the views. The numeral 1 designates the circular body, having a periphery 2 in a plane at a right angle to the open side 3 thereof and also provided with an inner plane face 4, parallel with the latter side. An offset 5, of circular form, also

merges into the plane face 4 of said body and is in concentric relation thereto, the outer surface of said offset being provided with a compound-curved periphery 6 and an outer flat face 7 and the inner surface of the same regularly curved in compound contour or composed of merging convex and concave curves which continue into the inner wall of a conical projection 8 of tubular construction. The said conical projection extends from the center of the offset 5, and the outer surface thereof regularly continues into the flat face 7 of the latter.

Having thus described the invention, what is claimed as new is—

The design for an earpiece for a telephone-receiver, herein shown and described.

In testimony that I claim the foregoing as my own I have hereto affixed my signature in the presence of two witnesses.

LUCIE HARDMON COALE.
